DRINKING CUP

Allen Levis and Robert Gordon, both of Cook County, Ill., assignors to Stuart-Allen Corporation, a corporation of Illinois

Filed July 22, 1966, Ser. No. 3,181

Term of patent 14 years

(Cl. D44—9)

FIGURE 1 is a side elevational view of a drinking cup showing our new design, the design on both sides of the cup being identical; and

The dominant features of our design reside in the portion shown in full lines.

We claim:

The ornamental design for a drinking cup, as shown and described.
